UNITED STATES PATENT OFFICE.

GEORGE BURNSIDE, OF SHINEY ROW, ENGLAND.

SAFETY BORING APPARATUS.

No. 882,741.

Specification of Letters Patent. Patented March 24, 1908.

Application filed November 26, 1906. Serial No. 345,272.

To all whom it may concern:

Be it known that I, GEORGE BURNSIDE, a subject of the King of Great Britain, residing at Milburn Terrace, Shiney Row, Fence 5 Houses, county of Durham, England, have invented a new and useful Safety Boring Apparatus, of which the following is a specification, such as will enable those skilled in the art to which it appertains to make and 10 use the same.

My invention relates particularly to improvements in boring apparatus designed for the purpose of making long bore holes either in rock or coal without danger to life 15 and loss of property which frequently results from accidents in operations of this class, and my invention is particularly designed to render work of this class safer and more expeditious than heretofore.

20 My invention is also designed particularly for use in connection with old mine workings, which frequently contain dangerous accumulations of water and gas under pressure, and my said invention is fully disclosed in the 25 following specification of which the accompanying drawings form a part, in which the separate parts of my improvement are designated by suitable reference characters in each of the views, and in which:

30 Figure 1 is a longitudinal side view of the complete apparatus which I employ and showing the method of operating the same, part of the construction being in section; Fig. 2 a view similar to Fig. 1, but showing 35 all the parts of the apparatus in horizontal section; Fig. 3 a cross section on the line 3—3 of Fig. 1; Fig. 4 a longitudinal section of a compound drill which I employ; Fig. 5 a side elevation of the compound drill 40 complete, and Fig. 6 a view similar to Fig. 1 but showing the initial step in the use of my improved apparatus, in which my compound drill is employed.

When beginning old mine workings or 45 borings, I first provide a machine stand or support 2, and feed screw 4, provided with a handle 1, and coupling box 5, all of well known construction, and employ in connection therewith a compound drill 6, comprising 50 a main tubular member 6^a and a drill point member 7 of less diameter than the main drill member, and the main drill member 6^a is provided with spiral wings or blades 51, which are staggered and overlapped so as 55 to prevent clogging in the operation of the drill as hereinafter described.

The drill point member 7 is of the same construction as the main part 6^a of the compound drill and is provided with similar wings or blades 51, and is screwed into the 60 main member 6^a, and is also provided at its outer end with a hole or support 8. The drill point member 7, which is tubular in form as shown in Fig. 4 is also provided with a longitudinal movable tubular valve 65 device 10, which is designed to close the communication between the parts 6^a and 7 of the compound drill, and is provided with a spiral spring 9, which normally holds said valve seated, and the said drill point member 7 is provided with interior grooves or ribs 7^a whereby water or other liquid is free to flow around the valve 10.

In practice the compound drill 6 is connected with the parts 2 and 4 by means of 75 coupling box 5 as shown in Fig. 6, and a drill hole 45 is bored part of which is of greater diameter than the other whereby an annular shoulder 45^a is formed in said drill hole. My invention also involves the details of construction shown in Figs. 1 to 3 whereby safety boring to any desired depth of the bore hole 45 is accomplished. These details involve a boring tube 41, provided with two metal wedge plates 17, provided at their 80 outer ends with hooks 50, and two supporting plates 18 also preferably provided at their outer ends with hooks 50, said wedge plates and supporting plates being adapted to be placed on the boring tube 41 and inserted into the larger part 45^b of the bore 85 hole. Connected with the outer end of the boring tube 41, is a cross head coupling 13, provided in its opposite sides with recesses 14, through which are passed screws 15, 90 connected with the hooks 50, of the wedge plates 17, and provided with nuts 38, and by turning the nuts 38 the plates 18 are expanded until the apparatus is securely locked 95 in the bore hole 45^b.

The inner end of the bore tube 41, is provided with a rigid collar 19, and two packing collars 20, of rubber or other suitable material, between which is placed a loose collar 21, preferably of brass, and before the apparatus is clamped in the bore hole 45^b as hereinbefore described the boring tube 41, is forced into the bore hole so that the inner packing ring or collar will press firmly on the shoulder 45^a, while the packing ring or collar 105 20 between the stationary metal collar 19 and brass collar 21, will be expanded out- 110

wardly against the walls of the bore 45^b and thus make a gas and water tight connection. Passing through the tubular boring tube 41, is a boring rod 46, which is connected with the compound drill 6, and is of less diameter than the boring tube 41, and which may be made up of separate sections, connected by couplings 47, and the boring rod 46 is connected with the feed screw 4, by means of a tubular pump spindle 28, which is connected with the feed screw by means of the coupling box 5, and the pump spindle 28, forms in effect, an extension of the boring rod 46, and mounted thereon is a pump 26, comprising a casing 26^a through which the spindle 28 passes and in which is a gland 26^b, and the casing 26^a is provided with a downwardly directed arm 26^c which carries a pump cylinder 26^d with the lower end of which is connected a water pipe 26^e, and the arm 26^c is provided with a passage 26^f, which communicates with the lower end of the cylinder 26^d. The cylinder 26^d is provided with the usual piston, with which is connected a rod 26^g which is connected with a band 26^h mounted on an eccentric sheave 26ⁱ, through which the pump spindle 28 passes and the said pump spindle is provided with ports or passages 26^j which communicate with the interior of the casing 26^a with which the passages 26^e in the arm 26^c also communicates, and in the casing 26^a at the end of the gland 26^b is placed a grooved and perforated sleeve 26^k which forms an additional packing for the casing 26^a and around and through which the water flows into the spindle 28. I also provide a coupling tube 35 adapted to be connected with the cross head coupling 13 and provided with oppositely directed plug or valve casings 35^a having caps through which are passed screws 37, provided with hand wheels 34, and with the inner ends of which are connected valve plugs 36, of rubber or other suitable material by means of which the passage through the tubular coupling 35 around the bore rod 46 which passes therethrough may be closed, and connected with the tubular coupling 35, is a valve casing 12 through which the boring rod also passes, and which is provided with a valve 12^a through which said boring rod also passes, and connected with the valve casing 12 is a stuffing box 22, through which the boring rod 46 passes, and it will be observed that the bores or passages through the boring tube 41, the cross head coupling 13, the tubular coupling 35, the valve casing 12, and the valve 12^a are all of the same size and much larger in diameter than the boring rod 46. A drain pipe 11 is connected with the coupling tube 35, adjacent to the cross head coupling 13, and provided with a valve 11^a, and a pressure gage 16 is connected with the cross head coupling 13.

65 In practice the compound drill 6 is first

used as shown in Fig. 6 to bore the holes 45 and 45^b to a predetermined depth thus forming the shoulder 45^a. In this operation, the machine stand or support 2 is mounted at the desired point in the mine chamber and is rigidly held in place by means of a screw device 2^a adapted to bear on or enter the roof wall of the mine. After the boring holes 45 and 45^b are bored to a suitable depth the compound drill 6 is detached from the feed screw 4, and the boring tube 41 having the expansion plates 18 and wedge plates 17 mounted therein is inserted so that the packing rings 20 will form a tight joint around the inner end of said boring tube as hereinbefore described, and all the parts of the apparatus are assembled as shown in Figs. 1 and 2, and the nuts 38 are turned so as to pull the wedge plates 17 outwardly and expand the plates 18 and hold the apparatus firmly in position. In assembling the parts as shown in Figs. 1 and 2, the part 6^a of the compound drill is left out and the part 7 only employed and this may be made of any desired length by connecting separate parts. In connection with the machine stand or support 2 a tapped feed nut 42 is also employed through which the feed screw passes, and in practice the feed screw may be operated either by the handle 1 or in any other suitable way, or by means of a power device if desired. When the feed screw 4 is turned as described the drill 7 is fed forwardly and the hole 45 is bored to the desired depth and in this operation water is pumped up through the pump 26 and through the drill rod 46 and through the drill 7, and passes out through the aperture 8 where it mingles with the debris produced by the drill point, flows back through the bore tube 41 to the discharge pipe 11. In this operation the pump is prevented from turning on the spindle 28 by means of a rod 3 connected with the machine stand or support 2 and with the valve casing 12 at 32, and passing through a guide 3^a connected with the casing 26^a of the pump and through which the rod 3 passes. The drill or drill point 7, as shown in Figs. 1 and 2, may be made either with double or single wings or blades 51, and to avoid clogging, parts of the wings or blades are cut away so that the parts remaining will overlap in such manner as to permit the liquid and debris to pass back through the boring tube 41. It will be understood that the valve 10 and spring 9 is used in the part of the drill as shown in Figs. 1 and 2, and the object thereof is to avoid the inside of the boring rod 46 from becoming clogged when being inserted into the bore hole 8. Whenever necessary the boring rod may be disconnected from the pump spindle 28 which forms a continuation thereof, and a new section of boring rod inserted so as to enable the boring to continue, and this may be 130

done without interfering in any way with the other parts of the apparatus, and this operation may be continued until the desired depth of boring is reached, or until old workings or mine chambers are bored into, and in this case the pressure of gases or air in such old workings or mine chambers will be indicated by the gage 16. Should there be an outrush of gas or water at any time 10 while the stuffing box 22 is disconnected for any purpose, the valve plugs 36 may be manipulated for closing the passage through the bore tube 41, and the valve 12^a may be used for closing the passage through the bore tube 41 and parts connected therewith when the boring rod 46 is withdrawn for any purpose.

Having fully described my invention, what I claim as new and desire to secure by Letters 20 Patent, is:—

1. In a boring apparatus of the class described, a tubular boring rod, a screw for feeding the same forwardly, a pump mounted on a movable spindle connected with said

rod and said feed screw, means whereby the pump is operated by the operation of said feed screw, spindle and boring rod, and means to prevent the pump from turning with said parts.

2. In a boring apparatus of the class described a tubular drill provided at one end with a point and at the other end with an inner annular shoulder, and a valve movable in said drill and provided with a spring whereby it is normally held seated on said shoulder.

3. In an apparatus of the class described, a stationary pump mounted on a rotatable spindle, said spindle being provided with an eccentric disk by which the piston of the pump is operated, and the cylinder of the pump being in communication with the interior of said spindle.

GEORGE BURNSIDE.
